UNITED STATES PATENT OFFICE.

LEONARD M. MARQUART, OF GEORGETOWN, MINNESOTA.

RIDING HARROW.

1,323,481.

Specification of Letters Patent.

Patented Dec. 2, 1919.

Application filed January 7, 1919. Serial No. 270,032.

To all whom it may concern:

Be it known that I, LEONARD M. MARQUART, a citizen of the United States, residing at Georgetown, in the county of Clay and State of Minnesota, have invented new and useful Improvements in Riding Harrows, of which the following is a specification.

This invention comprehends generally improvements in that class of inventions known as harrows and diggers and more particularly relates to a riding harrow.

It is the principal aim and object of the present invention to provide a device of the above mentioned character designed so that the body of the harrow may be raised or lowered and maintained in a lowered active position or a raised inactive position, permitting of the harrow being drawn in an inactive position over a field when it is not desired to use the same thus avoiding the inconvenience of loading and unloading the harrow body.

It is an equally important object of this invention to provide a device of the above mentioned character wherein the raising and lowering means is of novel construction and is positioned within convenient reach of the driver of the device so that the harrow may be readily and quickly placed in a raised or lowered position, when desired.

It is a more specific object of this invention to provide co-operative means on the harrow and on the frame for operably connecting the harrow to the frame; and to also provide a harrow frame of an improved construction.

Among the other aims and objects of this invention may be recited the provision of a device of the character described with a view to compactness, and in which the parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and ar-

rangement of parts may be made without departing from the principle of operation of the various parts.

The invention is clearly illustrated in the accompanying drawings, in which:

Figure 1 is a front end elevation of the invention.

Fig. 2 is a top plan view thereof.

Fig. 3 is a side elevation of the invention.

Fig. 4 is a perspective detail of the means for connecting the harrow to the frame, and

Fig. 5 is a perspective detail of the means for locking the harrow in a raised position.

Similar characters of reference are employed in all of the above described views, to indicate corresponding parts.

Referring now, more particularly, to the accompanying drawings, there is provided a main supporting frame generally indicated by the numeral 1 of a substantially rectangular configuration preferably comprising side pieces 2 embodying upper bars 3 and lower bars 4 the end portions of which latter are off-set upwardly and arranged in close relation with the end portions of the upper bar 3 while journaled through the looped terminals 5 of the bars 3 and 4 are the vertical shanks 6 of caster axles 7 the lower ends 8 of which serve to rotatably support caster wheels 9. The shanks 6 are formed with collars 10 for supporting the lower bars 4 while set-screws 11 are mounted through the looped terminals of the upper bars 3 and frictionally engaged with the shanks 6 to clamp the shanks of either the front or the rear wheels rigid with respect to the side pieces 2. Handle bars 12 are connected to the opposed front axles and also to the opposed rear axles and serve as a means for shifting or steering the device, as is apparent. The upper bars 3 and the lower bars 4 are connected by elongated cross-bars 13 and 14 while the upper cross-bars 13 are braced with respect to the lower cross-bars 14 by means of tie rods 15 and vertical bars 16, the tie rods being arranged at an incline as indicated. The upper and lower bars 3 and 4 are rigidly connected to the end of the vertical bars 16 by means of braces 17. Longitudinally disposed bracing bars 18 are arranged between the upper bars 13 and the lower bars 14 to increase the rigidity of the frame.

The harrow proper comprises a body 19 from which depend teeth 20. Hooks 21 ex-

tend from the forward ends of the harrow body 19 at suitable intervals from the ends thereof and engage with connecting elements generally indicated by the numeral 22 carried at suitably spaced intervals on the draw bar 23. These connecting elements 22 consist of a horizontally disposed loop 24 and a right angularly extending shank 25 which terminates at its upper terminal 5 in a hook 26. Fasteners 27 are employed for securing the connecting elements near the point of juncture of the hook with the shank, being anchored in the draw bar. Arms 28 depend from the forward lower 10 cross-bar 14 at suitably spaced intervals and terminate in horizontally disposed eyes 29 in which are engaged the shanks 25 of the adjacent connecting elements 22 while the hooks 26 thereof serve to prevent accidental 15 displacement of the shanks yet by reason of the elongated shanks raising and lowering of the harrow body 19 is permitted in a manner that will become apparent.

In order to raise and lower the harrow 20 chains 30 and 31 are employed. Outer terminals of the chains 30 are anchored to the outer longitudinally disposed lower bars 18 and extended downwardly and trained about pulleys 32 on the harrow body 19, the chain 25 being thence extended upwardly and trained about the pulley wheel 33 on the before mentioned longitudinally disposed bar and thence extended transversely of the device 30 being finally trained about one of the drums 34 in the locking and retaining body 35. The chain 31 is connected to one of the medial and lower longitudinally disposed bars 18 as at 36 and is extended downwardly and trained about a pulley wheel 37 on the 40 harrow body, being thence extended upwardly and trained about a pulley wheel 38 on the bar 18 near the point of connection 36 and the chain 31 is finally extended to the locking body and trained about another one 45 of the drums 34 therein. This locking body 35 is mounted on the intermediate upper longitudinally disposed bar 18 of the frame while the top 40 thereof is provided at points opposite the opposed drums 34 with 50 inwardly extending slots 41 in which the links of the chains may be anchored. It is apparent that there are two sets of chains 30 and 31 the other set being of similar construction and connected in a similar manner 55 to the other side of the harrow while handles 42 are connected to the terminals of the chains 30 and 31 in a position in proximity to the driver's seat 43 so that the driver may at any time grasp the handles so as to pull 60 the chains and consequently raise the harrow body 19 upwardly from the ground while the chains may be manipulated so that the links thereof may be locked in the slots 41 of the locking and retaining body 35.

A clevis 44 is connected to the draw bar 23 and is adapted to receive a draft device of conventional form.

It is believed in view of the foregoing description that a further detailed description 70 of the operation of the device is entirely unnecessary. Likewise it is believed that the advantages of the invention will be readily apparent.

As many changes could be made in the 75 above construction and many apparently widely different embodiments of this invention could be made without departing from the scope thereof it is intended that all matter contained in the above description or 80 shown in the accompanying drawings shall be interpreted as illustrative and not in a limited sense. It is also to be understood that the language used in the following claims is intended to cover all the generic 85 and specific features of the invention herein described and all statements of the scope of the invention which as a matter of language might be said to fall therebetween.

What is claimed is:

1. A device of the character described including a wheeled frame, a toothed harrow body operably connected to and positioned beneath the frame, a locking body connected to the frame the top of which is provided 95 with slots, a plurality of drums journaled in the locking body and opposed to the slots, chains having their outer terminals connected to the frame and being operably connected to the harrow body and the frame 100 and trained about the drums, handles connected to the inner terminals of the chains for exerting a pull on the chains for raising the harrow body, and certain links on the chains being engageable with the slots in 105 the locking body to assure of the maintenance of the harrow body in a raised position, when desired.

2. A device of the character described comprising a wheeled frame, a harrow body 110 having teeth projecting therefrom and disposed beneath the frame, means for operably connecting the harrow body to the frame, flexible elements operably arranged between the frame and the harrow body, handles connected to the inner terminals of the flexible elements for raising and lowering the harrow body, and means engageable with the flexible elements for releasably locking the harrow body in a raised position. 115

3. A device of the character described consisting of a rectangular wheel supported frame, a harrow body having teeth projecting therefrom disposed beneath the frame, means for operably connecting the harrow 125 body to the frame, a plurality of pulley wheels connected to the harrow body, a plurality of pulley wheels connected to the frame, chains anchored to the frame and trained about the pulley wheels on the har- 130

row body and the frame, a locking and retaining body the top of which is formed with slots, a plurality of drums journaled in the locking and retaining body opposite to the slots, the chains being trained about the drums and certain of the links thereof being insertible in the slots so as to assure of

the maintenance of the harrow body in a raised position relative to the frame, and handles connected to the inner terminals of 10 the chains for facilitating the manipulation of the chains.

In testimony whereof I affix my signature.
LEONARD M. MARQUART.
